UNITED STATES PATENT OFFICE.

JOHN H. ODELL, OF KINZUA, PENNSYLVANIA, ASSIGNOR OF ONE-THIRD TO GEORGE A. ODELL, OF SALAMANCA, NEW YORK.

CARBURETER.

1,135,815.

Specification of Letters Patent. Patented Apr. 13, 1915.

Application filed April 11, 1914. Serial No. 831,219.

To all whom it may concern:

Be it known that I, JOHN H. ODELL, a citizen of the United States, residing at Kinzua, in the county of Warren and State 5 of Pennsylvania, have invented certain new and useful Improvements in Carbureters, of which the following is a specification, reference being had to the accompanying drawings.

10. This invention relates to certain improvements in carbureters and has relation more particularly to a device of this general character especially designed and adapted for use in connection with an internal combustion engine, although it may be used for other purposes; and the object of the invention is to provide a device of this general character having novel and improved means whereby the mixture of air and fuel is effectively regulated, and wherein the flow of 15 the mixture through the intake pipe may be controlled with convenience and facility.

The invention consists in the details of construction and in the combination and 20 arrangement of the several parts of my improved carbureter whereby certain important advantages are attained and the device is rendered simpler, less expensive and otherwise more convenient and advantageous 25 for use, all as will be hereinafter more fully set forth.

The novel features of the invention will be carefully defined in the appended claim.

In order that my invention may be the 30 better understood, I will now proceed to describe the same with reference to the accompanying drawings, wherein—

Figure 1 is an elevational view, partly in section, of a carbureter constructed in accordance with an embodiment of my invention; Fig. 2 is a longitudinal sectional view taken through the upper portion of the intake pipe, and illustrating a form of valve control herein included; Fig. 3 is a horizontal section taken through the device as illustrated in Fig. 2, the valve members proper being shown in plan; Fig. 4 is a fragmentary elevational view, with a part in section, illustrating a further form of valve mechanism as herein included; Fig. 5 is a sectional view taken substantially on the line 5—5 of Fig. 4; Fig. 6 is a vertical sectional view

taken through the induction tip herein included, the needle valve being shown in elevation; and Fig. 7 is a sectional view taken substantially on the line 7—7 of Fig. 1.

As disclosed in the accompanying drawings, 1 denotes a casing of any predetermined configuration having depending from the base thereof and preferably adjacent one side, a nipple 2 adapted to be suitably connected with a suitable source of fuel supply and being provided at its inner end with the seat 3 with which is adapted to coat the valve 4 for controlling the admission of fuel within the casing 1. As herein disclosed, the valve 4 is carried by the lower extremity of a rod 5 extending through the casing and projecting exteriorly thereof, as indicated at 5^a, through a suitable opening 6 produced 10 in the casing. The rod 5 is adapted to rise and fall with the level of the fuel within the casing 1 in a manner which is believed to be self-evident and in order that this movement may be accomplished, I adjustably 15 mount upon the rod 5 within the casing 1 the float member 7, preferably of cork, having at its top an annular member 8 formed preferably of metal in threaded engagement with such rod, whereby it will be readily 20 perceived that the position of the float upon the rod may be varied in order to control the level at which the valve 4 will assume a closed position upon its seat 3. In order to maintain such float 7 in its adjusted 25 position, I find it of advantage to employ the jam nut 9 although any other means may be employed which will operate with facility. It will also be observed that by having the rod 5 projected exteriorly of the 30 casing, the valve may serve as a tickler.

Disposed through the casing at substantially the axial center thereof is the intake pipe 10, the lower end whereof being engaged by the nut 11 which serves as a medium to maintain such pipe 10 in operative position relative to the casing 1, and positioned within the portion of the intake pipe directed through the casing 1 is the induction tip or nozzle 12, herein shown as comprising a substantially L-shape tubular member having its foot open and directed through a side of the intake pipe in order to afford communication with the interior

of the casing 1. The stem 14 of the tip or nozzle is disposed on an inward taper and its upper extremity is provided with the oppositely disposed flanges 15 substantially 5 segmental in cross section, such flanges being disposed on downwardly converging planes and serving to deflect the air currents in order to afford a better mixture with the fuel drawn through the tip.

10 As herein disclosed, the foot 16 of the tip or nozzle projects exteriorly of the intake 10 and the periphery of such projected portion 17 is screw-threaded in order to be engaged by the conventional nuts 18 whereby such 15 tip or nozzle 12 will be maintained in operative position.

The casing 1 is capable of movement relatively to the pipe 10 after the nut 11 has been removed and in order that the nuts 18 20 may be readily applied or removed from the projected portion of the foot 17 of the tip or nozzle 12, I find it of advantage to annularly reduce a portion 10^a of the pipe, as is believed to be clearly shown in the accompanying drawings.

The flow of the fuel through the tip is under control of the needle valve 19 threaded through the foot 16 and projecting upwardly of the stem 14 of the tip or nozzle 30 and operating in a manner which is believed to be self-evident, the projected or exterior portion of the needle valve 19 being provided with a conventional milled head 20, for purposes which are believed to be self-evident.

As disclosed in the accompanying drawings, the intake pipe 10 exteriorly of the casing 1 is provided with a branch 21 disposed substantially at right angles thereof and 40 having its inner wall screw-threaded in order to have detachably position therein the valve seat 22 with which is adapted to coact the valve 23 carried on the inner end of the stem 24. The stem 24 is directed 45 through the guide yoke 25 integrally produced with the seat 22 and has its outer extremity screw-threaded in order to afford an adjustable connection for the nut 26. Interposed between the nut 26 and the yoke 50 25 is the expansible member 27, herein shown as a coiled spring, which serves to maintain the valve 23 normally in engagement with its seat 22. By having the nut 26 adjustable upon the stem 24, it will be 55 readily perceived that the tension of the expansible member 27 may be regulated.

In order to maintain the nut 26 in its adjusted position, I find it of advantage to employ a conventional jam nut 28. As is believed to be self-evident, the branch 21 60 serves as an air admission or supply port. The intake pipe 10 is also provided with the oppositely disposed alined branches 29 in which are mounted for sliding movement 65 the cylindrical members 30, the adjacent

ends of which being provided with the plates 31 adapted to overlie and having their free ends provided with the substantially semi-circular recesses 32 which are adapted to register upon outward relative 70 adjustment of the members 30 and thus effectively control the flow of the mixture through the intake pipe 10 in a manner which is believed to be self-evident. As herein disclosed, the relative movement of 75 the cylindrical members 30 is under control of the rock lever 33 pivotally mounted upon the intake pipe 10 exteriorly thereof and having oppositely directed link members 34 operatively connected with such members 80 30, while one extremity of such lever is operatively engaged with a rod 35 adapted to be manipulated in a manner which is believed to be self-evident. In order that no obstruction may be offered by the links 85 34 to the movements of the members 30, I have the outer extremities of the branches 29 provided with the open ended slots 36, as is believed to be clearly shown in the accompanying drawings. I do not wish to be 90 understood as limiting myself to the exact form of the members carrying the plates 31 as such intake pipe may be provided with flattened branches 29^a, as is shown particularly in Figs. 4 and 5, and in which instance 95 the members 30^a will be correspondingly formed.

From the foregoing description, it is thought to be obvious that a carburetor constructed in accordance with my invention is 10 of an extremely simple and comparatively inexpensive nature and is particularly well adapted for use by reason of the convenience and facility with which it may be assembled and by reason of the effectiveness with 10 which it performs its functions, and it will also be obvious that my invention is susceptible of some change and modification without material departure from the principles and spirit thereof and for this reason I do 11 not wish to be understood as limiting myself to the precise arrangement and formation of the several parts herein shown in carrying out my invention in practice.

I claim:

A device of the character described comprising a casing, a pipe disposed through said casing and having its lower end open, said casing being capable of movement relative to the pipe, an intermediate portion of 12 the pipe being annularly reduced, means for locking the casing against movement upon the pipe in one direction, a nozzle insertible within the pipe through the open end thereof, said nozzle comprising a substantially L-shaped tubular member, the foot whereof being disposed through and projecting exteriorly of a side of the pipe within the casing while the stem of the member is disposed on a taper, oppositely disposed seg- 13

mental flanges carried by the free extremity of the stem and overlying the upper end thereof, said flanges being disposed on downwardly diverging planes, and detachable means engageable with the projected portion of the foot of the member for maintaining said member in operative position.

In testimony whereof I hereunto affix my signature in the presence of two witnesses.

JOHN H. ODELL.
